UNITED STATES PATENT OFFICE.

JOHN R. WALL, OF AMERICUS, GEORGIA.

SIGN.

Application filed June 14, 1927. Serial No. 198,833.

This invention relates to means for displaying signs in the most advantageous places, without the use of tacks, staples, nails, screws, glue, and the like, and eliminates all damage to such places of attachment.

It is the object of my invention to provide new and improved means simple in construction and use, of the character mentioned, for clamping signs of various sizes to abutments and columns of various materials.

My invention consists in the novel arrangement of an adjustable clamping means, whereby a sign-holder can be clamped to an abutment without defacing or injuring the abutment.

The invention will be readily understood from the following description and its novel features pointed out in the claims, but it is to be understood that the invention is not confined to the exact features shown, as various changes may be made within the scope of the claims.

In the drawings:

Figure 1 is a front elevation of a favored modification of the invention, with a section of the sign cut away to show the arrangement of the clamping means.

Figure 2 is a cross section of the same taken in line 2—2 of Fig. 1.

Fig. 3 is a cross section of the same, taken in line 3—3 of Fig. 1.

Figure 4 is a front elevation of a modification of the invention clamped to an abutment of greater width than the sign-holder, with a section of the sign cut away to show the arrangement of the clamping means.

Figure 5 is a cross section of the same, taken in line 5—5 of Fig. 1.

Fig. 6 is a front elevation of a modification of the invention clamped to a column of less width than the sign-holder.

Fig. 7 is a cross-section of the same taken in line 7—7 of Fig. 6.

Fig. 8 is a cross-section of the same taken in line 8—8 of Fig. 6.

In the modification as shown in Figures 1, 2 and 3, the combination sign-holder frame 1, supporting sign 17, has perforations 2 in which is removably mounted the guide rod 3; the clamping members comprising angular rods 4 and 5, have outwardly extending arms 6 and 7 adjustably clamped to frame 1 by means of clamp 8 and screw 9, pass downwardly over rod 3

and bend backwardly perpendicular to the plane of frame 1, to form short arms 10 and 11 which carry the shoes 12 and 13 with perforations 14 for receiving the arms 10 and 11. The object of the shoes is to present a large bearing surface to the post or abutment 15 to prevent marring of the same by the arms 10 and 11.

The tension spring 16 is shown extended and adjustably attached to the rods 4 and 5 so as to pull them together, and is of sufficient strength to cause the shoes 12 and 13 to grip the abutment firmly, holding the sign in place. In clamping the invention to an abutment the rods 4 and 5 are slideable through the clamp 8, until the distance between them equals the width of the abutment.

In the modification as shown in Figures 4 and 5, the sign-holder frame 1, has perforations 2, in which are removably and adjustably mounted the clamping members comprising the rods 18 and 19 having eyelets 20 on their inwardly extending extremities connected by the tension spring 16; the outwardly extending extremities of the rods 18 and 19 are bent backward perpendicular to the plane of the frame 1 to form the short arms 20' on which are removably mounted the shoes 12 and 13. When clamping the sign-holder to an abutment like 21, the rods are pulled outwardly from the frame extending the spring, the sign placed flat against the abutment and the rods released. The rods because of the tension of the spring will move inwardly and cause the shoes to grip firmly the sides of the abutment, holding the sign in place.

In the modification as shown in Figures 6, 7 and 8, the sign-holder frame 1, has perforations in which is removably mounted the rod 3'; the clamping members comprising L-shaped rods 27 connected by tension spring 16 and shoes 12 and 13 removably mounted on the L-shaped rods, slidably engage the rod 3' by means of sleeves 28', the shoes gripping the opposite sides of the column 29. If the sign be very heavy I may employ a chain 28" and by attaching its ends to the rod 3' and extending it around the post or abutment 29 reinforce the attaching means and hold the sign-frame securely to the column by an interposed spring (not shown).

While I have shown and described sev-

eral desirable modifications of the invention, it is to be understood that this invention is not limited to any specific form or arrangement of parts except in so far as 5 such limitations are specified in the claims.

What I claim as my invention is:

1. An adjustable sign-holder, comprising a sign frame, opposing clamping members adjustably and removably mounted on said 10 frame to engage the opposite sides of an abutment, a rod mounted transversely on the frame, said clamping members slidably engaging the rod, and spring means normally drawing the clamping members together.

2. An adjustable sign holder, comprising a sign frame, angular rods slidably mounted in the frame and movable in opposite directions therein, said rods including arms 20 offset from the frame and in opposing relation to each other, shoes mounted on the arms in opposing relation, and spring means connected with the rods and normally tending to move the same in opposite directions 25 to effect a clamping action of the shoes.

3. An adjustable sign holder, comprising a sign frame, a guide rod secured transversely of the frame, angular rods slidably mounted in the frame and movable in opposite directions therein, said angular rods being 30 slidable on the guide rod and including arms in opposing relation to each other and offset from the frame, shoes mounted on the arms in opposing relation, and spring means connected with the angular rods and nor-

mally tending to move the same in opposite directions to effect a clamping action of the shoes.

4. An adjustable sign holder, comprising a sign frame, a guide rod secured transversely of the frame, angular rods slidably mounted in the frame and movable in opposite directions therein, said angular rods being 40 slidable on the guide rod and including arms in opposing relation to each other and offset from the frame, shoes mounted on the arms in opposing relation, spring means connected with the angular rods and normally tending to move the same in opposite 45 directions to effect a clamping action of the 50 shoes, and an adjustable clamp mounted on the frame to engage the angular rods to hold the latter in their adjustments.

5. An adjustable sign holder, comprising a sign frame, a guide rod secured transversely of the frame, angular rods slidably mounted in the frame and movable in opposite directions therein, means providing a 55 slidable engagement between the angular rods and the guide rod, said angular rods including arms in opposing relation to each other and offset from the frame, shoes mounted on the arms in opposing relation, and spring means connected with the angular rods and normally tending to move the 60 same in opposite directions to effect a clamping 65 action of the shoes.

In testimony whereof I affix my signature.

JOHN R. WALL.
